Inventor.

CALVIN W. SHERWOOD, OF CHICAGO, ILLINOIS.

Design No. 3,262, dated November 17, 1868.

DESIGN FOR THE STANDARDS OF A SCHOOL-DESK.

The Schedule referred to in these Letters Patent and making part of the same.

To all whom it may concern:

Be it known that I, CALVIN W. SHERWOOD, of the city of Chicago, Cook county, Illinois, have originated and designed a new and original Pattern or Design for Standards of School-Desks and Seats, which is fully, clearly, and exactly represented by the accompanying photographs of two figures which have been taken from one of the standards.

Figure 1 shows the seat turned down.

Figure 2 shows the seat turned up.

In the photographs the wood-portions of the desk and seat are shown, but I do not claim that my design includes anything except the iron parts or standards.

By an inspection of the drawings or photographs my new design will be fully understood, much better than from any written description.

I am now making five sizes of school-desks and seats, having standards like those represented; these I designate by the letters A, B, C, D, E, which are cast in the lower part of each standard, as shown, the letter A designating the largest size. Other sizes may be made, if desired.

What I claim as my invention, and desire to secure by Letters Patent, is—

The design or pattern for standards for school-desks and seats, substantially as described and shown.

C. W. SHERWOOD.
